UNITED STATES PATENT OFFICE.

THOMAS ELLIS BROWN, JR., OF MORRISTOWN, NEW JERSEY.

BASCULE-BRIDGE.

1,251,634.

Specification of Letters Patent.

Patented Jan. 1, 1918.

Application filed December 8, 1916. Serial No. 135,785.

To all whom it may concern:

Be it known that I, THOMAS ELLIS BROWN, Jr., a citizen of the United States, and a resident of Morristown, in the county of 5 Morris and State of New Jersey, have invented certain new and useful Improvements in Bascule-Bridges, of which the following is a specification.

This invention relates to improvements in 10 bascule bridges.

The simplest form of bascule bridge is the ordinary heel counterbalanced trunnion type, and this form is usually adopted when the height of the bridge above the water is 15 sufficient to admit of its use. In many situations, however, the height is insufficient for the heel of the bridge and counterbalance to clear the water or tops of the piers, and in such cases the span must be made longer in 20 proportion to the width of the waterway and a watertight pit must be provided into which the heel of the bridge and counterbalance may descend. The expense of construction in such cases becomes very great, 25 and therefore the more complicated and unsightly types, with towers and counterweights above the roadway, are usually resorted to.

Cases frequently occur where the height 30 above water is not sufficient for a simple heel balanced bridge of ordinary type, without watertight pits, and yet where the use of unsightly towers and counterweights would be very objectionable, and in ordinary heel 35 counterbalanced trunnion bridges it is necessary to so dispose the counter-balance that the center of gravity of the entire moving mass will coincide with the center of the trunnions or pivots, and this usually requires 40 the placing of a considerable portion of the counter-balance above the bridge deck, to the detriment of the appearance of the structure. It is therefore the object of my invention to produce a heel balanced trunnion bridge, suitable for such cases, in which 45 coincidence of the center of gravity and the pivot is unnecessary, and wherein therefore no counter-balance need be placed above the deck of the bridge, and by which also the 50 use of water tight pits or unsightly towers is entirely avoided.

To accomplish this object, I omit from the heel of the bridge, that portion of the counter-balance which it would be necessary to place above the floor level of the 55 bridge and also that portion which will not

clear the top of the pier, and substitute therefor an equivalent counter-weight pivoted to a fixed portion of the structure and placed below the deck of said fixed portion 60 and I operatively connect said weight to the moving portion of the bridge.

My construction is especially useful when concrete is employed for counter-balance (which is now the general practice) as, on 65 account of its great bulk, concrete counter-balance is very clumsy and unsightly when placed above the bridge floor.

Referring to the drawings which accompany the specification to aid the description, 70

Figure 1 is a side view of a bridge of my construction.

Fig. 2 is an explanatory diagram of my method of balancing, and Figs. 3 and 4 show adaptations of my invention to bridges 75 of very low elevation.

Similar letters of reference refer to similar parts in all the figures.

Referring to Fig. 1, B is a bascule bridge, P the pivot or trunnion about which it rotates, A, A² and A³ are piers and D¹ is a portion of the fixed structure which supports said pivot P. Such portions of said fixed structure as would interfere with the clearness of the drawing are indicated as 85 broken away.

H is that portion of the counter-balance or heavy material which may conveniently be placed in the rearwardly projecting end or heel of the bridge B, rotating with said bridge B; said counterbalance H being of such dimensions that it will clear said pier A and will not project above the roadway. W is a counter-weight which I prefer to use to complete the balance of the bridge, and 95 which I prefer to support on the frame K which rotates about a pivot or trunnion L, said pivot L being supported preferably on a portion of the fixed structure such as D².

C is a strut pivotally attached to said 100 counter-weight W at a point E at one end, and at the other end to the heel of the bridge B at a point I.

The positions of said pivot L of said counter-weight W and the points of attachment E and I of said connecting strut C are so chosen, with relation to the weight W and the trunnion P, as to cause said counter-weight W together with said heel counter-balance H to balance the bridge B in all its 110 poistions, as is hereinafter explained in connection with Fig. 2.

R and R^1 are fixed and movable portions respectively of the roadway or bridge floor, and Z being the break in the floor between them. Said break Z, said connecting strut 5 C and said counter-balance H are so located, that the said counter-balance H, strut C and end of said roadway R^1 , will clear each other and the tops of the piers A, and A^2 , when the bridge is rotated to its vertical position.

10 It will be understood that the aforesaid refers to one side of the bridge only; and that the parts described for one side will generally be duplicated on the other side of the bridge; but it will generally be preferable when using materials of low specific 15 gravity (such as concrete) for counter-balance, to extend said counter-balance H and weight W the full width of the bridge.

The bridge may be operated in any suitable manner, but I prefer to use a gear segment 20 M secured to the bridge and meshing with a pinion N on shaft O supported on a fixed part of the structure. Said shaft O may be rotated by any suitable gearing 25 and power.

When said pinion N is rotated in the direction the reverse of the motion of the hands of a clock, said bridge B rises and said heel counterbalance H descends; said 30 strut C moves downwardly and passes under said pivot P and said counterweight W descends. When said pinion N is rotated in the opposite direction bridge B descends and said counterbalance H and weight W rise.

35 Said bridge B, counterbalance H, weight W and strut C are shown in dotted lines in the positions they occupy when the bridge is completely opened to its vertical position.

Now, referring more especially to Fig. 2, 40 to more fully explain the principle of counterbalancing the bridge in all its positions, and how the construction hereinbefore described is arrived at, *c. g.* is the center of gravity of the uncounterbalanced bridge 45 B, and P is the pivot or trunnion around which said bridge rotates. In order that said bridge B shall be balanced in all its positions by means of a counterbalance placed in the heel or rearwardly projecting 50 end of said bridge, said heel counterbalance must be of such weight and be so placed as to make the center of gravity of the total rotating mass coincide with the pivot P; and therefore the center of gravity J of such a 55 heel counterbalance as a, b, c, d must lie on the prolongation of the line drawn from *c. g.* through the trunnion P, as indicated in Fig. 2, and also said center of gravity J of such a heel counterbalance must be sufficiently 60 far back of the trunnion P to make the moment of said heel counterbalance around the pivot or trunnion P equal to the moment of the bridge B around said pivot or trunnion P.

65 The rectangle, a, b, c, d , represents a sim-

ple heel counterbalance of such mass, and with its center of gravity J so placed on the line *c. g.*, P prolonged, as to balance the bridge. It will be obvious from the Fig. 2 that such a counter-balance a, b, c, d , which we may call the theoretical counter-balance, cannot be used under the conditions shown as it projects above the roadway R and extends back so far that it would collide with the pier A were the bridge to be opened to 75 a vertical position. I therefore omit the interfering portion b, c, d, h, e, f , of the said theoretical counter-balance a, b, c, d , leaving the non-interfering portion a, f, e, h , which we will hereinafter designate as 80 counter-balance H. I substitute for the omitted portion b, c, d, h, e, f , of said theoretical counter-balance, an equivalent but not necessarily equal, counter-weight W, which I place in a convenient position, preferably beneath the fixed portion R of the roadway as shown in Fig. 1, and also in Fig. 2, and support said weight W on a pivot or trunnion L carried by some suitable part of the fixed structure, as D^2 in Fig. 90 1. The center of gravity G of said weight W should have the same angular position with relation to said pivot L as the center of gravity *g* of said omitted portion b, c, d, h, e, f , would have had to the trunnion P. 95 I connect said weight W by means of a compression strut C to the heel of the bridge B, placing said strut C parallel to the line L—P joining the centers of the respective pivots of the counter-weight W and bridge 100 B, and place the connections E and I at equal distances from the trunnions L and P respectively, and so that said strut C will clear the piers A and A^2 when the said weight W and bridge B rotate around their 105 respective pivots L and P. With this arrangement the angular motion of the weight W around the pivot L will be the same as the angular motion of the omitted portion of the theoretical counter-balance b, c, d, h, e, f , would have been around the pivot P, and by making the weight W of proper amount so that its moment around the pivot L, *i. e.* its weight multiplied by its lever arm, is equal to the moment that the said omitted 110 portion would have had around the pivot P, then the said weight W and the heel counterbalance H will together balance the bridge 115 in all its positions.

While I prefer to use as much heel counter-balance H as can conveniently be placed on the rearwardly extended end of the bridge B, it will be readily understood that any desirable amount of the theoretically necessary heel counterbalance a, b, c, d , may 125 be omitted and replaced by equivalent weight in the counter-weight W; and we may also, in cases where the head room is unusually low, use a series of counter-weights, W^1, W^2, W^3 , operatively connected 130

together, as shown in Fig. 3 by the struts C¹—C²—C³, and in such cases we may omit the entire heel counter-balance, and replace it by such a series of weights, W¹, W², etc., by making their total effect the equivalent of said theoretical counter-balance, a, b, c, d.

Cases may occur where the height above the water is insufficient even for the arrangements shown in Figs. 1 and 3, and we may 10 then use the approach span as a counter-weight as shown in Fig. 4. In such cases I prefer to pivotally support the rearward end of said approach span in the frame K, (see Fig. 4) and pivotally connect the forward 15 end of said approach span to the heel or rearwardly projecting end of the bridge at S, as by this construction the entire weight of said approach span is made effective in counter-balancing the bridge, part of said 20 weight acting directly at S and the remaining part at I by means of the strut C. The weight of said approach span may be increased by the addition of concrete or other heavy material as indicated in Fig. 4.

25 Now having described my improvements, I claim as my invention.

1. In a bascule bridge, the combination of a counter-weight pivoted to a fixed portion of the bridge structure, and an operative connection from said counter-weight to the rearwardly extended end of the movable part of said bridge, said connection being parallel to the line joining the pivot of the counter-weight and the pivot of the bridge 35 in all positions of said bridge.

2. In a bascule bridge, the combination of a counter-weight pivoted to a fixed portion of the bridge, and an operative connection between said counter-weight and the heel 40 or rearwardly projecting end of the movable portion of said bridge, adapted to move said counter-weight with the same angular motion as the angular motion of said heel end of said bridge.

45 3. The combination in a bascule bridge, having one end extended rearwardly beyond the pivot of said bridge, of a counter-weight pivoted to a fixed portion of the structure, and an operative strut connection between 50 said counter-weight and said rearwardly extended end of said bridge.

4. The combination in a bascule bridge having one end extended rearwardly beyond its pivot, of a counter-weight pivoted to a 55 fixed portion of the structure, said counter-weight being located below the floor of said fixed portion, and an operative strut connection between said counter-weight and the rearwardly extended end of said bridge.

60 5. The combination in a bascule bridge having one end extended rearwardly beyond

its pivot, of a counter-balancing weight on said rearwardly extended end, a counter-weight pivoted to a fixed portion of the structure, and an operative strut connection 65 between said counter-weight and the rearwardly extended end of said bridge.

6. The combination in a bascule bridge having one end extended rearwardly beyond its pivot, of partly counter-balancing material on said rearwardly extended end, a counter-weight pivoted to a fixed portion of the structure, and an operative strut connection between said counter-weight and said rearwardly extended end of said bridge, 70 said counter-balancing material and said counter-weight being placed below the roadway of said bridge.

7. The combination in a bascule bridge having one end extended rearwardly beyond its pivot, of a plurality of pivoted counter-weights disposed below the roadway of said bridge and operatively connected to each other and to the rearwardly extended end of said bridge so as to counterbalance 85 said bridge in all its positions.

8. In a bascule bridge, the combination of a counter-weight pivoted to a fixed portion of the bridge structure and located below the roadway of said bridge, and an operative connection from said counter-weight to the movable part of said bridge, said connection being parallel to the line joining the pivot of the counter-weight and the pivot of the bridge in all positions of said bridge. 95

9. In a bascule bridge, a counter-weight pivoted to a fixed portion of the bridge and located below the roadway of said bridge, and an operative connection between said counter-weight and the heel end of the movable portion of said bridge, and said operative connection being adapted to move said counter-weight with the same angular motion as the angular motion of the heel end of said bridge. 100

10. In a bascule bridge, the combination with a pivoted bridge structure of a partial counter-balancing weight thereon, a supplementary counter-balance weight pivoted on a stationary structure, and an operative connection between said partial counterbalancing weight and said supplementary counter-balance weight positioned parallel to the straight line through said pivots and equal in length to the distance between said pivots. 115

Signed at New York city, in the county of New York, and State of New York, this sixth day of December, A. D. 1916.
